(57) **CLAIM**

The ornamental design for a cockpit window panel, as shown and described.

DESCRIPTION

FIG. 1 is a forward view into an aircraft cockpit showing our new design of a cockpit window panel;

FIG. 2 is a forward view into an aircraft cockpit with an instrument panel removed for showing the cockpit window panel of FIG. 1;

FIG. 3 is a perspective view showing the left side of the cockpit window panel of FIG. 1;

FIG. 4 is a perspective view showing the right side of the cockpit window panel of FIG. 1;

FIG. 5 is a left side view of the cockpit window panel of FIG. 1;

FIG. 6 is a right side view of the cockpit window panel of FIG. 1; and,

FIG. 7 is a close-up view of a portion of the cockpit window panel shown in FIG. 3.

In FIGS. 1-7, the dash-dash broken lines illustrate portions of the cockpit window panel that form no part of the claimed design. The dot-dash broken lines illustrate the periphery of the enlarged views of the cockpit window panel and form no part of the claimed design.

1 Claim, 7 Drawing Sheets
